UNITED STATES PATENT OFFICE.

ROBERT WEISS, OF NEWARK, NEW JERSEY, ASSIGNOR OF ONE-HALF TO MATTHEW TANZOLA, OF NEWARK, NEW JERSEY.

DESIGN FOR A COMBINED STORM AND GLARE SHIELD.

Application filed September 19, 1922. Serial No. 3,762. Term of patent 14 years.

To all whom it may concern:

Be it known that I, ROBERT WEISS, a citizen of the United States, residing at Newark, in the county of Essex and State of New Jersey, have invented a new, original, and ornamental Design for a Combined Storm and Glare Shield, of which the following is a specification, reference being had to the accompanying drawing, forming part thereof.

Fig. 1 is a perspective view of the shield.

Fig. 2 is an end elevation thereof.

Fig. 3 is a sectional elevation thereof.

I claim:

The ornamental design for a combined storm and glare shield, as shown.

ROBERT WEISS.
